UNITED STATES PATENT OFFICE.

JOHN HENRY WHITMYER, OF JOHNSTOWN, NEW YORK.

RAIL-JOINT BED-PLATE.

SPECIFICATION forming part of Letters Patent No. 699,905, dated May 13, 1902.

Application filed August 29, 1901. Serial No. 73,755. (No model.)

To all whom it may concern:

Be it known that I, JOHN HENRY WHITMYER, a citizen of the United States, residing at Johnstown, county of Fulton, and State of New York, have invented a certain new and useful Improvement in Rail - Joint Bed-Plates, of which the following is a specification.

My invention relates to a new and useful improvement in rail-joint bed-plates, and has for its object to provide a plate which is adapted to lie underneath the flange of the rails and extend across the joint between the two rails for the purpose of preventing the rails at this point from sagging and strengthening the joint.

With these ends in view this invention consists in the details of construction and combination of elements hereinafter set forth and then specifically designated by the claim.

In order that those skilled in the art to which this invention appertains may understand how to make and use the same, the construction and operation will now be described in detail, referring to the accompanying drawings, forming a part of this specification, in which—

Figure 1 is a perspective view of a section of railway-rails, showing my invention applied thereto; Fig. 2, a cross-section through railroad-rails having my invention applied thereto, and Fig. 3 is a perspective view of the bed-plate.

The bed-plate consists of the flat strip A, which has formed upon each end the extension B upon one side and the turned-over lip C upon the other side. The extension B and the turned-over lip C upon one end are upon the opposite sides to the extension and lip upon the other end of the plate. The ends of the rails are adapted to rest upon the plate A and the joint between the rails to come about in the center of the same. The width of the plate A is exactly the same as the width of the flange of the rail. The turned-over lip C is adapted to embrace the flange of one of the rails upon one side, and the other turned-over lip upon the other end of the bed-plate is adapted to embrace the flange of the other rail upon the opposite side. The

extensions B have holes D formed through the same, and the ends of the bed-plate are each adapted to rest upon the ties, and through the holes D are adapted to be driven ordinary railroad-spikes, the head of which will engage the flange of the rails and by passing through the holes will hold the bed-plate in position relative to the rails. The turned-over lip C engaging the flange of the rail upon one side and the spike upon the other will prevent any lateral movement, and by reason of the spike passing through the bed-plate into the tie the bed-plate will also serve to hold the rails against any lateral movement.

The advantage of my invention is that the bed-plate will strengthen the joint and also prevent the rails from sagging at the joint, and therefore prevent any unevenness of the rails, which will add to the comfort of the passengers by reducing the jolting of the train.

Another advantage of my invention is that the bed-plate can be stamped or rolled and made very cheaply and can be easily replaced should one become damaged.

Of course I do not wish to be limited to the exact construction here shown, as slight modifications could be made without departing from the spirit of my invention.

Having thus fully described my invention, what I claim as new and useful is—

In a railroad-joint bed-plate consisting of a flat metallic strip of about the same width as the flange of the rail, a turned-over portion formed upon one side of one end of the strip, another turned-over portion formed upon the other side of the other end of the strip, an extension formed upon each end of the strip upon the side opposite to the turned-over portion, holes formed through said extension, substantially as and for the purpose specified.

In testimony whereof I have hereunto affixed my signature in the presence of two subscribing witnesses.

JOHN HENRY WHITMYER.
